UNITED STATES PATENT OFFICE.

HENRY H. HERBOLD, OF THAYER, AND CHARLES HEGNER, OF CAINESVILLE,
MISSOURI; SAID HERBOLD ASSIGNOR TO SAID HEGNER.

SAFETY-STOP FOR MINE-CARS.

1,019,249.

Specification of Letters Patent.

Patented Mar. 5, 1912.

Application filed December 15, 1911. Serial No. 666,008.

To all whom it may concern:

Be it known that we, HENRY H. HERBOLD and CHARLES HEGNER, citizens of the United States, HENRY H. HERBOLD residing at 5 Thayer, Oregon county, Missouri, and CHARLES HEGNER at Cainesville, in the county of Harrison and State of Missouri, have invented certain new and useful Improvements in Safety-Stops for Mine-Cars, 10 of which the following is a specification.

This invention relates to that class of stop devices for mine cars which are designed to prevent the cars from being precipitated into an open shaft, and it is the object of 15 the invention to provide a simple, reliable and efficient device of this kind.

In order that the invention may be better understood, reference is had to the accompanying drawing, in which—

20 Figure 1 is an elevation showing the application thereof. Fig. 2 is a cross-section on the line 2—2 of Fig. 1.

Referring specifically to the drawing, 5 denotes a mine-shaft, and 6 is a gallery leading therefrom. In the gallery are laid rails 7 on which the mine car 8 runs. The stop device is located in the gallery a short distance from where it opens into the shaft, and it comprises the following parts: To 25 one of the rails 7 is pivoted at one of its ends, as indicated at 9, a lever 10 which extends at its other end for a short distance into the shaft 5, and carries at the last-mentioned end a bumping post 11. The lever 30 extends horizontally and is pivoted to swing in a vertical plane. Intermediate its ends, the lever carries an upstanding buffer horn or abutment 12 which normally extends alongside the rail into the path of the car 40 wheel so as to engage the latter and stop the car. The lever works in a pit 13 beneath the floor 14 of the gallery, said floor having an opening 15 through which the lever extends downward at its pivoted end, 45 into the pit. The floor also has an opening to accommodate the abutment 12.

To the bottom of the floor 14 is rigidly secured a plate 16 carrying depending rods 17 which extend into the pit and carry a plate 18 at their lower ends. The plate 16 50 has a slot 19 through which the abutment 12 extends. The lever 10 is held against lateral displacement by being located between the rods 17, a pair of said rods being carried by each end of the plate 16. Between the top of the plate 18 and the bottom of the lever 10 is located a spring 20 which serves to normally hold the lever in elevated position, in which position of the lever the abutment 12 is in the path of the 60 car wheel, and thus serves as a stop for the car, as already described. The spring 20 may be a V-leaf spring or any other type of spring, and it is fastened at its ends to the lever 10 and the plate 18. The base and 65 head of the rail are recessed on one side as indicated at 21, in which recesses the abutment 12 works, thus bringing the latter directly in the path of the car wheel, and making it impossible for said wheel to pass when 70 the abutment is in elevated position.

The abutment 12 is normally in elevated position, so that the car cannot run into the shaft 5. When the descending cage (not shown) strikes the post 11, the lever 10 is 75 swung downward, whereupon the abutment 12 is lowered to release the car and enable the latter to be run on the cage. As the cage ascends, the spring 20 pushes the lever upwardly and the abutment is again placed in 80 operative position, ready to stop the next car.

The device herein described is devoid of complicated parts to get out of order, and it is therefore safe and reliable, and it effectually serves the purpose for which it 85 is designed. The device can also be applied to the mouth of the shaft, and it is adapted for all kinds of mine cars.

The drawing shows only one of the rails equipped with the device, but it will be understood that the other rail may be similarly equipped.

2
We claim:

1. A car stop comprising a support, rods depending from the support, a plate carried by the rods, a lever pivoted to swing in a vertical plane between the rods, a spring between the lever and the aforesaid plate, and an abutment rising from the lever.
2. A car stop comprising a slotted support, rods depending from the support, a plate carried by the rods, a lever pivoted to swing in a vertical plane beneath the support and between the rods, a spring between the lever and the plate, and an abutment rising from the lever and passing through the slot of the support.

In testimony whereof we affix our signatures in presence of two witnesses.

HENRY H. HERBOLD.

his

CHARLES X HEGNER.
